UNITED STATES PATENT OFFICE.

ISAAC WHITE, OF WILMINGTON, DELAWARE.

LOCK.

1,378,504.

Specification of Letters Patent. Patented May 17, 1921.

Application filed June 30, 1920. Serial No. 392,974.

To all whom it may concern:

Be it known that I, ISAAC WHITE, a citizen of the United States, residing at Wilmington, county of New Castle, and State 5 of Delaware, have invented a new and useful Improvement in Locks, of which the following is a full, clear, and exact description, reference being had to the accompanying drawings, which form a part of this 10 specification.

This invention relates to an improvement in locks, and more particularly to locks for doors.

The object of my invention is to provide 15 a lock having a spring latch for latching the door and which is arranged to be actuated by pressure applied to the door, whereby I am enabled to dispense with the usual knobs together with their latch-actuating 20 mechanism.

A further object of my invention is to provide a lock having a combined latching and locking bolt, which is arranged to latch the door when in one position and to lock 25 the door when in another position.

The precise nature of my invention will be best understood by reference to the accompanying drawings which will now be described, it being premised, however, that 30 various changes may be made in the details of construction, without departing from the spirit and scope of my invention as defined in the appended claims.

Figure 1 is a face view of one form of lock 35 made in accordance with my invention, with the cover plate removed and in which the door and the door jamb are shown in section.

Fig. 2 is a sectional view on the line 2—2 40 of Fig. 1.

Fig. 3 is a similar view on the line 3—3 of Fig. 1.

Fig. 4 is a view similar to Fig. 1 in which I have shown the bolt thrown by the key 45 to lock the door.

Fig. 5 is a face view of the lock in the door.

Fig. 6 is a sectional view on the line 6—6 of Fig. 4.

50 In these drawings the reference character 10 designates the door and 11 the jamb of the door, with the usual slotted plate 12 connected thereto.

Seated within an opening in the door 55 10 is one form of my improved lock having a casing 13 provided with a cover 14 which

is secured to the casing 13 by the screws 15. 16 is the usual front plate of a mortise lock such as shown, and 17 are screws for securing the lock to the door. 60

Slidably mounted within the lock case is a combined latch and lock bolt, having a yoke 18 and a bar 19 extending rearwardly therefrom. 20 is a roller pivotally mounted between the ends of the yoke 18 and which 65 forms a latch for the door when the door is to be merely latched, as hereinafter described.

The horizontal portions of the bolt yoke are slidably mounted in slots in the front 70 plate 14 which form guides therefor, while the rear portion of the bolt is guided on a projection 21 on the casing, and which is seated in a slot in the bar 19.

Pivotally mounted on a pin 22 on the 75 casing is a lever 23, having a downwardly and forwardly extending portion 24, the forward end of which bears against the yoke 18, when the lock is in latching position. The upper portion of the lever 23 extends 80 over the bar 19, while the downwardly and forwardly extending portions are somewhat narrower and lie between the bar and the side of the casing, there being a detent 25 formed at the end of the wider portions. 85 This detent 25 is seated in recess 26 in the upper face of bar 19, when the bolt is in latching position, and in a similar recess 27, when the bolt is in the locked position.

28 is a spring within the case which bears 90 against the lever 23 to hold the detent 25 in the recesses 26 and 27, as shown in Figs. 1 and 4, respectively.

The door and casing 13 are provided with 95 registering key holes for the reception of a key 29 to actuate the bolt to lock the door, or to place the bolt in its latching position.

When the door is latched as shown in Figs. 1 and 2, the roller 20 merely enters the opening in plate 12 and is restrained 100 against further outward movement by the detent 25 and is at the same time yieldingly held against further inward movement by the end of the forwardly extending member 24 of lever 23, which engages the back 105 of the yoke. The door can be opened by moving the door on its hinges, which will force the roller 20 out of the opening in the plate 12 against the action of the spring 28 through the medium of the lever 24, the 110 end of which is engaged by the yoke 18 and rocked about the pivot 22, and raise the

horizontal portion of the lever 23 against the action of the spring 28. This action of the lever will withdraw the detent 25 from recess 26 and place the yoke 18 under 5 the action of the spring, and as soon as the roller has cleared the plate 12, the spring 28 will force the yoke forwardly until the detent 25 enters the recess 26 which will prevent further movement thereof. The 10 latching force of the bolt can be varied by changing the spring 28 to increase or decrease the pressure of the lever 23 on the yoke 18.

When it is desired to lock the door, the 15 bolt is advanced into the opening in the jamb 11 by means of the key 29, which first engages the member 24 of lever 23, and raises it, together with the detent 25, to first release the bolt, and then advances the bolt 20 to the position shown in Fig. 4 by engaging the wall of a recess 30 in the bar 19. The bolt will be retained in this position by the engagement of the detent with the walls of the recess 27, and in order to slip the bolt, 25 it will be necessary to first raise the lever 23, which can be done with the key when turning it in the reverse direction and the further movement of the key will return the bolt by engagement with the side of the recess 30.

In the drawings the lower surface of the forwardly extending portion 24 of the lever 23 is flat, but it will readily be understood that this surface may be of any desired 35 shape, while the engaging face of the key would be correspondingly shaped.

The advantages of my invention result from the provision of a lock having a combined latching and locking bolt, which is 40 arranged to latch the door when in one position and lock the door when in another position. Also from the provision of a spring actuated lever, which is arranged to maintain the bolt under spring pressure when 45 in its latching position, and to lock the bolt, when the bolt is in its locking position. Further, from the provision of a locking bolt and spring lever arranged to be actuated by a key to first release the bolt and 50 then shift it from one position to the other.

Having now fully described my invention, what I claim and desire to protect by Letters Patent is:

1. A lock having a casing, a sliding bolt, 55 a spring actuated lever pivoted to the casing, a detent on said lever, a plurality of recesses in the bolt arranged to be engaged by the detent to lock the bolt in different positions, and means on the lever for maintaining the bolt under spring pressure in one direction when in one position.

2. A lock having a casing, a single bolt arranged to latch a door when in one posi-

tion and to lock the door when in another position, a spring pressed lever pivoted to 65 the casing and arranged to maintain the bolt in latching position and hold it against being shifted into locking position, and co-acting means on the bolt and lever for locking the bolt when in its locking position. 70

3. A lock having a casing, a single bolt arranged to latch a door when in one position and to lock the door when in another position, a spring pressed lever pivoted to 75 the casing and arranged to maintain the bolt in latching position and hold it against being shifted to locking position, and key surfaces on the lever and bolt arranged to first actuate the lever to release the bolt and to then shift the bolt when engaged with a 80 key.

4. A lock having a casing, a bolt arranged to be placed in either locking or latching position, key engaging means for shifting the bolt from one position to the other, and 85 a spring-actuated lever pivoted to the casing for retaining the bolt in either position and for permitting the bolt to be moved to unlatched position and for retaining the bolt in its latched position. 90

5. A lock having a casing, a bolt arranged to be placed in either locking or latching position, key engaging means for shifting the bolt from one position to the other, recesses in said bolt, a lever pivoted to the casing and having a detent for engaging said recesses for retaining the bolt in its locking position and for restraining the bolt from moving from its latching position to its locking position, a spring for retaining the lever in its normal position, and a projection on the lever for engaging the bolt when in latching position for yieldingly holding it in such position. 100

6. A lock having a casing, a bolt arranged to be placed in either locking or latching position, key engaging means for shifting the bolt from one position to the other, a spring-actuated lever pivoted to the casing, means on the lever and bolt for retaining the bolt in its locking and latching positions, and means on said lever arranged to be engaged by the key to first release the bolt before the bolt is shifted by said key. 105

7. A lock having a casing, a bolt arranged to be placed in either locking or latching position, key engaging means for shifting the bolt from one position to the other, and a spring lever pivoted to the casing for retaining the bolt in locking position and for yieldingly holding said bolt in latching position. 115

In testimony of which invention, I have hereunto set my hand, at Wilmington, Del., on this 28th day of June, 1920.

ISAAC WHITE.
